UNITED STATES PATENT OFFICE.

FRANCIS D. DEVLIN, OF NEW HAVEN, CONNECTICUT, ASSIGNOR TO NATIONAL FOLDING BOX COMPANY, OF NEW HAVEN, CONNECTICUT, A CORPORATION OF NEW JERSEY.

COUNTER DISPLAY FOLDING BOX.

1,379,395.

Specification of Letters Patent. Patented May 24, 1921.

Application filed June 11, 1920. Serial No. 333,225.

To all whom it may concern:

Be it known that I, FRANCIS D. DEVLIN, a citizen of the United States, and a resident of New Haven, New Haven county, State of Connecticut, have invented a new and useful Counter Display Folding Box, of which the following is a specification.

My invention relates to that class of folding, usually paper, boxes, or containers, supplied with means for supporting them, as upon a merchant's counter, in inclined positions, facilitating display of their contents to customers, and its objects comprise supplying such means which are not only more economical in manufacture, and more stable and more attractive in appearance as such supports, but also are capable of alternatively serving the additional purpose of a cover for the box, and this more sanitarily and with less injury to, or molestation of, the contents than heretofore.

I attain these, and other useful, objects by constructing my box and its appurtenances as follows, reference being had to the accompanying drawings which are designed to illustratively disclose a type thereof embodying my universally applicable, novel principles of construction, the said type being one in which, as is preferable, the container, and all of its said accessories, or appurtenances, are unitary, being cut and formed as a naturally coherent unit out of a single sheet of paper, strawboard, or other suitable material.

Referring now to the drawings:

Figure 1 is a plan view of the so cut and formed "blank" of my box before it is "set up,"

Fig. 2 is a partly perspective and partly sectional view showing one half of the box after it has been "set up," and my novel flaps disposed to act as a cover therefor, the section being taken transversely of the middle of the box;

Fig. 3 is a perspective frontal view of the box when the flaps have been positioned and interlocked to serve as an easel support to display the contents of the box;

Fig. 4 is a perspective view principally of the rear of the box, the parts in the same positions as in Fig. 3;

Fig. 5 is a transverse sectional view of Fig. 4 taken on a plane located at the line

5—5 thereof and seen in the direction of the arrow.

The "blank" shown in Fig. 1 is cut from the sheet of paper, or other material, and creased, or scored, by any of the present approved means and methods. The rectangular portion B serves as a side, in this instance as the bottom, of the box; C, C', as the ends. Between these parts the material is, as usual, creased, or scored, as at 7, 7, to impart flexibility without breakage, the result being that said sides are up-bendable relatively to said bottom. The end pieces C, C', each carry an in-folding extension, 8, the material being creased between them as at 9, 9, and one of the end pieces, in this instance C', carries another side T, T', of the box, in this instance the top, having an opening, O, for display therethrough of the contents of the box. This opening, in the present instance extends medially well across the entire top, thus practically dividing the latter into the two sections respectively designated T, T', as above. The top carries extensions, *i. e.*, the sides proper, 10, 10, of the box, and the part T' a securing flap 11, the material being creased, or scored, as at 12, between the end C' and the top, and also between the latter and its said extensions and flap. The extensions 10, 10, each carry an inlay 13, the material being creased, or scored, as at 14, between them. The bottom B, being the side of the box opposite the opening, carries projecting from opposite sides thereof other than the sides carrying the ends C, C', side extensions, or flaps, comprehensively designated by F, F', the material thereof being creased, or scored, as at 15 so that the said flaps are bendable relatively to said bottom in either direction. The flap F' comprises a component 16 and a thereby carried extension 17, carrying tongues, 18, 18. The flap F' comprises between its components 16 and 17 a crease, or score, 19, which is parallel with a side of the side, or bottom, B of the box, and also, in its component 16, a crease, or score, 20, which is, as shown, diagonal to said side.

The flap F comprises a component 21, carrying an extension, 22, containing a slot, 23, and carrying a further extension, or prolongation, 24, containing two slots 24', 24''. The flap F contains a crease, or score, 25,

which is parallel with, and also a crease, or score, 26, diagonal, as shown, to, a side of the bottom, or side, B of the box. The flap F contains also in its component 21 a slot 27. All of the slots referred to are positioned and dimensioned so as to be entered by the tongues 18, and the parts by this means interlocked in various positions as hereafter described.

10 The material is, between the components 22 and 24, scored, or creased, as at 28, and preferably more deeply than in the other instances, so as to enable the part 24 to be readily severed from the remainder of the 15 box.

The blank, having been produced as above described, is folded upon the crease line 7 between B and C' and the securing flap, 11, being bent over to underlie C, is secured to 20 the latter, preferably by a suitable adhesive.

To set up the blank from its thus collapsed state to that employable as a box, the bottom B is suitably supported, say in horizontal presentation, the ends C, C', up-

25 raised therefrom until vertical, the extensions 8, 8, inturned to right angles with said ends, the extensions 10, 10, downturned vertically and the inlays 13, 13, meanwhile simultaneously inturned and in- 30 serted between the bottom edges of 8, 8, and the bottom B, thus locking these parts into a box form.

The flaps F, F', are then manipulated as follows, viz:

35 1. To function as a cover, the flaps are turned, or folded, inward until their respective component parts 16 and 21 contact in parallelism with the outer surface of the sides 10, 10. The extensions 17 and 22 40 are then further bent, or folded, respectively upon the crease lines 19 and 25 until the extension 22 and its prolongation 24 overlie the opening of the box and the tongue carrying extension 17 overlies the prolongation 24. The tongues 18, 18, are then inserted in 45 the slots 24', 24'' and the box and its contents are thus securely covered, Fig. 2 illustrating the relative positions of the parts when thus interlocked for the purpose last 50 specified;

2. To function as a support for the box in its inclined, or display, position, the tongues 18, 18, are withdrawn from the slots, 24', 24'', thus unlocking the flaps. 55 The latter are bent backward beyond the outer surface of the bottom of the box. The prolongation 24 of the flap F is bent backward on the crease, or score, 28, until its surface contacts flatly with the surface of 60 the extension 22 of the component 21 of the flap F; the component 21 is then bent upon the diagonal crease, or score, 26, until one end of the prolongation 24 contacts with the outer surface of the bottom B of the box. The component 16 of the flap F' is then

bent inward upon its diagonal crease, or score, 20, and therewith its extension 17, until one of the tongues 18 registers with the slot 27 of the component 21 of the flap F, into which said tongue is then inserted; the other tongue 18 is then in register with, and is inserted into, the slot 23 of the extension 22 of the flap F, thus locking the parts into position in which they are thus adapted to serve as a support, or easel, 75 tilting the box and its contents into an inclined position such as to facilitate the display of the latter, Figs. 3, 4 and 5 illustrating the respective positions of the various parts when arranged and interlocked for 80 the purpose last described.

The construction and forms are such as to be exceptionally economical of stock or material required to accomplish the purposes described. They are also permissive of "finishing" the surface of the stock, and of doing all the lithographing and printing, 95 on one side only of the blank, thus also contributing to economy.

The interlocked covering of the opening of the box, and of its contents, by the flaps and their transposition and interlocking to serve as backbraces, or supports, for the box in its inclined, or display, position, are rendered exceptionally easy to the unskilled and not destructive of the parts, which can be repeatedly employed to perform their respective cover, and brace, functions. The form and construction are also particularly advantageous from the points 100 of view of cleanliness and sanitation in that the necessity in previous display boxes of forcing portions of the cover or of the easel braces into contact with the contents of the box is obviated; and the box is, in its inclined position, more strongly and stably supported than heretofore.

In cases in which the re-covering is not desired, after display, the prolongation 24 of the flap F may be advantageously torn 110 off along the crease, or score, 28, the latter being, for this reason cut, or indented, deeper than the other creases.

Having now described my invention, what I claim as new and desire to secure by Letters Patent is the following, viz:

1. A rectangular collapsible paper box having in its top an opening for display therethrough of the contents, and a bottom carrying a pair of flaps projecting therefrom and dimensioned and shaped to fold in one direction and overlap each other as a cover for said opening, and in the opposite direction as a support for the box in inclined position; and means carried by said flaps to interlock them in each of their said respective positions.

2. A rectangular collapsible paper box having in its top an opening for display therethrough of the contents, and carrying a 130

- pair of flaps projecting from the bottom thereof and dimensioned and shaped to fold in one direction and overlap each other as a cover for said opening, and in the 5 opposite direction as a support for the box in inclined position, each of said flaps containing a crease, or score parallel with, and also one diagonal to an edge of said bottom; and means integral with said flaps to inter- 10 lock them in their said respective positions.
3. A collapsible unitary paper box comprising a rectangular bottom portion bend- ably carrying projecting from opposite sides thereof two opposite ends of the box and, 15 projecting from the opposite sides thereof other than the sides carrying said ends, side extensions, or flaps, each comprising a crease, or score, which is diagonal to, and a crease, or score, which is parallel with an edge of said bottom, one of said flaps containing 20 slots, and the other of said flaps carrying tongues disposed to coöperate with each other to interlock the flaps, and the said flaps being dimensioned so as to, overlap- pingly cover the top of the box when bent 25 in one direction, and when bent in the opposite direction overlappingly interlock behind the bottom and in a plane inclined thereto.

FRANCIS D. DEVLIN.
